UNITED STATES PATENT OFFICE.

CARL CAPPEL, OF PITTSBURG, PENNSYLVANIA.

DESIGN FOR A CONFECTION-DISH.

SPECIFICATION forming part of Design No. 22,601, dated July 11, 1893.

Application filed June 21, 1892. Serial No. 437,547. Term of patent 7 years.

To all whom it may concern:

Be it known that I, CARL CAPPEL, a citizen of the United States, residing at Pittsburg, in the county of Allegheny and the State of Pennsylvania, have invented and produced a new and original Design for a Dish for Confections, &c., of which the following is a specification, reference being had to the accompanying drawing for a clear and full understanding of the invention, in which the figure is a perspective view of my dish, the shape and configurations representing the front, side, and roof of a building.

The principal features of my design and the novelty reside, especially, in the shape and ornamental configurations on the dish.

In the drawing, A is the dish of rectangular form and consisting of three stories, a, b, c, a roof c', and a handle d. The horizontal lines B, on the front and side of the house represent the dividing lines between the stories. The front and side of the house have configurations e to represent a brick front, and rectangular shaped configurations f, f', at the corners and base of the building to represent stone trimmings.

g, are rectangular shaped windows, there being three windows in a row and equi-distant apart, as shown, on the front, and three

on the side of each story, with the exception 30 of the front of the lower story which has two windows and a door h, between the windows. This door has ornamentations h', h³, representing rectangular parallelograms, h³ being composed of small squares, and a square h², 35 intermediate of the other two, of similar construction. Over the windows and door are ornamentation representing stone trimmings j, of the shape of trapezoids with heart shaped figures k, in the center thereof, and scrolls l, 40 on each side of the figure.

m, is a cornice of well known curved form, situated underneath the projecting edges of the roof of the building.

C' is a hipped roof with a rectangular shaped 45 handle representing a chimney situated on its apex.

Having described my invention, what I desire to secure by Letters Patent is—

The design for a confection dish, as herein 50 shown.

In testimony that I claim the foregoing I hereunto affix my signature this 12th day of May, A. D. 1892.

CARL CAPPEL. [L. S.]

In presence of—

GEO. JOHNSTON,
G. H. ALEXANDER.
